UNITED STATES PATENT OFFICE.

GODFRIED LAUBE, OF SANTA MONICA, CALIFORNIA, ASSIGNOR TO MARKUS D. FEATHER AND HATTIE R. LAUBE, OF SANTA MONICA, CALIFORNIA.

COMBINED PEN AND PENCIL HOLDER.

No. 852,514.

Specification of Letters Patent.

Patented May 7, 1907.

Application filed January 22, 1907. Serial No. 353,429.

To all whom it may concern:

Be it known that I, GODFRIED LAUBE, a citizen of the United States of America, residing at Santa Monica, in the county of Los Angeles and State of California, have invented certain new and useful Improvements in Combination Pen and Pencil Holders, of which the following is a specification, reference being had therein to the accompanying drawing.

This invention relates to combination pen and pencil holders, and the invention has for its object to provide a holder for detachably holding a pencil and pen.

Another object of this invention is to provide a combination pen and pencil holder that can be easily and quickly secured in a pocket without cutting or tearing the fabric of the pocket.

My invention aims to provide a simple and inexpensive lead pencil holder for holding the pencils of different colors, as black, red, blue, etc., the pencils being detachably mounted in the holder whereby they can be easily reversed to protect the points thereof. To prevent the pencils from being forced inwardly too far when in a reverse position, the holder is provided with means for limiting the inward movement of the pencils. In connection with the holder, I use a pen which can also be reversed. In order that the holder can be easily used I provide the ends of the holder with small protuberances or serrations, the roughness of which is for the purpose of giving a firm hold to the fingers and thumb so that the holder cannot possibly slip when in use.

A particular feature of my invention resides in the fact that extremely short pieces of pencil can be used in the holder, and that the holder is always maintained approximately the same length, thereby making it never awkward to handle. By providing a means for using the otherwise useless bits of pencil I encourage economy, both in the fact that the points are protected and that small pieces of pencil can be used.

With these and other objects in view which will more readily appear as the invention is better understood, the same consists in the novel construction, combination and arrangement of parts to be hereinafter more fully described and then specifically pointed out in the appended claims.

Referring to the drawing forming part of this specification, like numerals of reference designate corresponding parts throughout the several views, in which:

Figure 1 is a side elevation of my improved combination pen and pencil holder, Fig. 2 is a plan of the same, Fig. 3 is a bottom plan, Fig. 4 is a cross sectional view taken on the line $x-x$ of Fig. 1, Fig. 5 is a similar view taken on the line $y-y$ of Fig. 1, Fig. 6 is a longitudinal sectional view taken on the line $z-z$ of Fig. 2.

My improved pen and pencil holder is constructed of light and durable metal, as gold, silver, brass, copper, aluminium, tin, and the holder comprises practically three pieces, two pieces of sheet metal and a piece of resilient wire. One piece of sheet metal is oblong in plan and is stamped and bent to form a tube 1, having its end serrated, roughened or provided with closely arranged protuberances 2, said protuberances covering approximately two-thirds of the tube and leaving a central smooth surface 3. The protuberances 2 are employed for preventing the holder from slipping while being used. The ends of the tube 1 are reamed or flanged as at 4, to add rigidity to the tube, dispense with the sharp edges thereof and provide a neatly finished article. The central portion of the tube is provided with inwardly extending lugs or teats 5, to limit the movement of the pencil section 6 and the pen section 7 when inserted in the tube or holder.

The pencil section 6 consists of an ordinary pencil having a holder tip 8, while the pen section 7 comprises an ordinary pen holder having a rubber tip 9, the rubber tips 9 being inserted in the tube or holder when the pen and pencil are being used. When the pen and pencil are not in use the pen and pencil are reversed and placed in the tube 1 to protect the pen and pencil points and prevent them from being injured or injuring a person carrying the holder.

The central portion of the tube 1 is provided with a semi-cylindrical sleeve 10, which comprises one of the pieces of the holder. This sleeve is soldered or suitably secured to the holder and has its longitudinal edges reamed, as at 11 to embrace the ends 12 of a resilient U-shaped spring 14, the U-shaped end of said spring being slightly curved as at 15, to normally lie in engagement with the

central portion of the tube 1. The spring 14 is employed to retain the holder in engagement with a person's pocket, the holder either being supported upon the outer side of the pocket or upon the inner side of the pocket. The fabric comprising the outer side of the pocket is adapted to lie between the central portion of the tube and the spring 14, the spring firmly retaining the holder in engagement therewith.

From the novel construction of my improved holder it will be observed that very short pencils can be used in the holder and that when the holder is laid upon a desk or inclined surface, such as the top of a school desk, it will be impossible for the same to roll and become broken by striking the floor or furniture in close proximity to the desk. Further, the article is practically indispensable to persons having use for pens and pencils owing to the fact that the pen or pencil, or both, are always in position, neatly secured in the pocket of a vest or coat and may be easily detached when to be used and that the point of either the pen or pencil is never damaged.

My improved article or holder is also adapted as an advertising novelty as the central portion of the holder comprises a space in case it is desired to place an advertisement upon the holder.

The holder may be finished in gold, silver, nickel-plate, japanned or painted, according to one's esthetic tastes.

While I have herein described the holder as for pens and pencils it is obvious that it may be used for either and that the same may be made of any desired length, and proportion, and that such changes in the details, as are permissible by the appended claims, may be resorted to without departing from the spirit and scope of the invention.

What I claim and desire to secure by Letters Patent, is:—

1. A combined pen and pencil holder consisting of a slotted tube having reamed ends, closely arranged protuberances carried by the ends of said tube, inwardly projecting lugs carried by said tube, a sleeve soldered to the central portion of said tube, a U-shaped curved spring secured to the edges of said

sleeve and engaging the central portion of said tube, a pen detachably mounted in one end of said tube, and a pencil detachably mounted in the opposite end of said tube, substantially as described.

2. A combined pen and pencil holder consisting of a slotted tube, protuberances carried by the ends of said tube, inwardly projecting lugs arranged centrally of said tube, a sleeve secured to said tube, a curved spring secured to said sleeve, a pen detachably mounted in the end of said holder, and a pencil detachably mounted in the opposite end of said holder.

3. A combined pen and pencil holder consisting of a tube having serrated or roughened ends, a sleeve secured to the central portion of said tube, a spring carried by said sleeve, a pen detachably mounted in one end of said tube, and a pencil detachably mounted in the opposite end of said tube.

4. A pen and pencil holder, comprising a tube slotted from end to end, having a roughened exterior surface at the ends and a smooth intermediate or central portion, a semi-cylindrical sleeve fixed on the tube at said smooth central or intermediate portion, and a clasp carried by said semi-cylindrical sleeve.

5. A holder of the type described embodying a tube, having slotted and roughened ends, a sleeve carried centrally of said tube, and a curved U-shaped spring carried by said sleeve.

6. As a new article of manufacture, a holder embodying a slotted, roughened tube having reamed ends, and a spring attached centrally of said tube.

7. A pen and pencil holder comprising a tube slit at the ends, a semi-circular sleeve secured to the tube approximately at the center thereof, and a U-shaped spring engaging the tube having its ends secured to said sleeve and constituting clasp.

In testimony whereof I affix my signature in the presence of two witnesses.

GODFRIED LAUBE.
